UNITED STATES PATENT OFFICE.

CHARLES SCHLOSSOW, OF DETROIT, MICHIGAN, ASSIGNOR TO STANDARD SANITARY MANUFACTURING COMPANY, OF PITTSBURG, PENNSYLVANIA, A CORPORATION OF NEW JERSEY.

DESIGN FOR A FLUSHING-TANK.

SPECIFICATION forming part of Design No. 35,899, dated May 6, 1902.

Application filed April 14, 1902, Serial No. 102,938. Term of patent 7 years.

To all whom it may concern:

Be it known that I, CHARLES SCHLOSSOW, a citizen of the United States, residing at Detroit, in the county of Wayne and State of Michigan, have invented and produced a certain new and original Design for a Flushing-Tank, of which the following is a specification, reference being had therein to the accompanying drawing, in which the figure is a perspective view.

A is a body of general rectangular form. B and C are respectively the top and bottom, both of which project outward beyond the front of the body and have correspondingly-shaped edges, and D represents ornamental vertical columns extending across the front, on opposite sides thereof, and between said projecting top and bottom. E is a plain-faced depressed panel in said front, between said columns and projecting top and bottom, having an ornamental border.

The leading feature of the design is the body of general rectangular form having projecting top and bottom portions, with correspondingly-shaped edges, and ornamental vertical columns extending between said projecting top and bottom portions upon opposite sides of the front, and a plain panel between said top, bottom, and columns having an ornamental border. 25 30

What I claim as my invention is—

The design for a flushing-tank, substantially as herein shown and described.

In testimony whereof I affix my signature in presence of two witnesses.

CHARLES SCHLOSSOW.
